UNITED STATES PATENT OFFICE

CLARENCE F. WIGREN, OF TEANECK, NEW JERSEY, ASSIGNOR TO THE SUPERHEATER COMPANY, OF NEW YORK, N. Y.

BOILER AND SUPERHEATER

Application filed April 5, 1930. Serial No. 441,851.

My invention relates to a combined boiler and superheater and aims to provide an arrangement whereby a given degree of superheat may be attained with a comparatively compact superheater arrangement protected from excessive temperatures by steam generating tubes.

The novel features of my invention are pointed out in the appended claims. The invention, however, together with further objects and advantages, will best be understood from a detailed description of a specific arrangement embodying my invention and such a description will now be given of an illustrative embodiment of the invention portrayed in the accompanying drawings in which

Fig. 1 is a vertical elevation of a boiler and superheater arrangement in accordance with my invention, one side wall of the boiler setting being removed for purposes of illustration, and

Fig. 2 is a fragmentary detail showing an alternative arrangement of the superheater.

The arrangement illustrated in the drawings comprises a boiler having a horizontal cross drum 10 with downcomer nipples 12 depending therefrom and connecting into the tops of vertical headers 14. Extending laterally from headers 14 are tubes 16 forming a tube bank which curves upwardly so that the upper ends of the tubes 16 connect into horizontal headers 18 under the roof 20 of the boiler. Headers 18 are connected to the drum 10 by horizontal steam and water circulator nipples 22.

Connecting into the bottoms of vertical headers 14 and extending downwardly therefrom is a set of short vertical nipples 24 which connect into the tops of another set of vertical headers 26. Extending laterally from the headers 26 beneath the tube bank 16 is a group of tubes 28—28 forming a slag screen bank immediately above the furnace chamber 30. As shown, tubes 28 are straight and horizontally inclined and project at their upper ends laterally beyond the horizontal projection of the headers 18 on bank 28. At their upper ends the tubes 28 connect into a third group of vertical headers 32 from the upper

ends of which extend steam and water circulator nipples 34 which run upwardly and curve horizontally beneath the roof 20 to a connection with the horizontal headers 18 previously mentioned. Owing to the fact that tubes 28 extend laterally beyond the perpendicular from the end of headers 18 farthest from the headers 14, a chamber 36 is formed above the upper ends of tubes 28 and between the nipples 34 and the bank 16. I have found that such a chamber is a desirable location for a superheater. Owing to the fact that the chamber 36 is above the slag screen 28, superheater elements in such chamber are protected from excessive temperatures, but, as the ordinary slag screen bank is not thick, the gases leaving it on its upper side have a considerable temperature, especially when the boiler is operating at high rating. A superheater in chamber 36 therefore can be designed with comparatively small heating surface for a given degree of superheat and capacity. In the arrangement illustrated, a superheater having elements 38 is placed in the chamber 36 and suspended by hangers 40, 40 from beams in or above the roof of the boiler.

It is recognized as highly desirable that superheater elements should be drainable, and I have found that a chamber in the position of chamber 36 lends itself readily to the installation of a drainable superheater. As shown, the superheater in chamber 36 has an upper header 42 and a lower header 44, the ends of the elements 38 preferably being connected into the headers 42 and 44 at the bottom and top respectively, to facilitate connection and disconnection of the elements. The headers 42 and 44 may be conveniently run horizontally along the outer wall 46 of the boiler at one end thereof.

The individual elements 38 extend in zig-zag arrangement between the headers and are so arranged that there is no slope in any of the straight pipe lengths in the direction from the bottom header 44 to the top header 42 and so that the bends between the straight pipe lengths avoid all traps for liquid flowing from one of said headers to the other, and are therefore completely drainable.

Preferably the boiler illustrated in the drawings is provided with internal baffling to direct the gases in an efficient manner over the generator tubes and over the superheater elements 38. As shown, the baffle 48 runs horizontally along the top of the slag bank 28 from the headers 26 to a point approximately in the middle of the slag screen bank, at which point baffle 48 is connected with baffle 50 running sharply upward along the outer edge of the tube bank 16 and assisting in defining the chamber 36. Baffle 50 is terminated a sufficient distance below the headers 18 to provide ample space for the gases to pass around the upper end of such baffle and depending baffle 51 runs downwardly from the roof on the other side of tubes 16 from baffle 50 and roughly parallel to it to provide a down pass through the bank 16 on one side of baffle 51 and an up pass on the other side of baffle 51 reaching to an uptake 52.

By reason of the fact that no generator tubes intersect the space occupied by superheater 38, such elements lose a minimum of heat by radiation, so that the superheater elements can have a minimum heat absorbing surface for a given degree of superheat and capacity.

In Fig. 1, the headers 42 and 44 for the superheater elements are alongside the front wall of the boiler and the end portions of elements 38 extend through wall 46 into chamber 36. This arrangement enables the superheater elements to be of the drainable type. The invention is not limited to the feature of a drainability, however, and in Fig. 2, I have illustrated a fragment of a boiler which will be understood as identical with that shown in Fig. 1. In Fig. 2, however, the headers 42' and 44' for the superheater elements are shown immediately above the roof 20 of the boiler and the end portions of superheater elements 38' extend downwardly through roof 20 into the chamber 36.

I claim:

1. The combination with a boiler having a tube bank all the tubes of which extend between lower vertical headers and upper horizontal headers, means for causing thermal circulation in said bank when heated, a slag screen below said bank and projecting laterally therefrom at one end, and means for causing a thermal circulation through said slag screen bank when heated, said last means forming with said banks a chamber, of a superheater in said chamber above said second bank.

2. The combination as set forth in claim 1 and in which the elements of the superheater are drainable.

3. The combination of a boiler having a horizontal cross drum, a tube bank all of whose tubes extend between vertical headers at one end and horizontal headers at the other end, connections between said headers

and said drum for completing the thermal circulation of said bank, a slag screen bank below said first mentioned bank and having connections with said drum for completing its thermal circulation, the connections of said slag bank including elements forming with the upper ends of the tubes of said first bank a chamber above the slag bank, headers on the outside of said chamber and superheater elements within said chamber and connected to said outside headers. 70 75

4. The combination as set forth in claim 3 and in which the superheater elements are drainable.

5. The combination with a boiler having a tube bank all the tubes of which extend between lower vertical headers and upper horizontal headers, said tubes having upturned portions for connecting with said horizontal headers, means for causing thermal circulation in said bank when heated, a slag screen bank below said bank and projecting laterally therefrom at one end, means for causing thermal circulation through said slag screen bank when heated, said last means forming with said banks a chamber, of a baffle extending along a portion of the upper surface of said slag screen bank and running upwardly therefrom close to the upturned portions of the tubes in said first bank along the inner edge of said chamber, and a superheater in said chamber above said second bank. 80 85 90 95

6. The combination of a boiler having a horizontal cross drum, a tube bank all of whose tubes extend between vertical headers at one end and horizontal headers at the other end, said tubes having upturned portions for connecting with said horizontal headers, connections between said headers and said drum for completing the thermal circulation of said bank, a slag screen bank below said first mentioned bank and having connections with said drum for completing its thermal circulation, connections of said slag bank including elements forming with the upper ends of the tubes of said first bank a chamber above the slag bank, a baffle extending along a portion of the upper surface of said slag screen bank and running upwardly therefrom close to the upturned ends of said first bank and along the inner edge of said chamber, headers on the outside of said chamber, and superheater elements within said chamber and connected to said outside headers. 100 105 110 115 120

7. The combination with a boiler having a set of substantially horizontal and a set of substantially vertical headers, a group of generating tubes connected with said headers and having its tubes turned upwardly at one end for connecting with said horizontal headers, means for causing a thermal water circulation through said group when the group is heated including a drum and 125 130

circulator nipples connecting said headers and drum, a slag screen bank below said group and extending beyond the upturned ends of the tubes of said group at one end of the boiler, and circulators connecting said slag bank and said headers, of a superheater above the extended portion of said slag screen, and baffling for causing hot gases to pass upwardly through said screen and over said superheater and then over the upturned ends
10 of the tubes of said group.
